ADDRESS DUPLICATING APPARATUS

Hubert Jagger, Maywood, Ill.

Application October 1, 1949, Serial No. 5,253

Term of patent 7 years

(Cl. D64—11)

To all whom it may concern:

Be it known that I, Hubert Jagger, a citizen of the United States and resident of Maywood, in the State of Illinois, have invented a new, original, and ornamental Design for Address Duplicating Apparatus, of which the following is a specification, reference being had to the accompanying drawing, forming a part thereof.

Figure 1 is a top plan view of an address duplicating apparatus showing my new design.

Fig. 2 is a side elevational view of the same.

Fig. 3 is an elevational view of one end of the apparatus, and

Fig. 4 is an elevational view of the other end thereof.

The side of the apparatus not shown in the drawing corresponds to the side shown in Fig. 2 and the portion of the bottom of the apparatus not shown in Fig. 2 corresponds to the portion illustrated in said figure.

I claim:

The ornamental design for an address duplicating apparatus, substantially as shown and described.

HUBERT JAGGER.
